UNITED STATES PATENT OFFICE

2,368,625

ELECTRONIC TRANSFORMER

Charles F. Wilcox, Cambridge, Mass.

Application August 11, 1942, Serial No. 454,465

1 Claim. (Cl. 250—27.5)

The invention relates to electronic devices, and more particularly to an electronic transformer, the primary object of the invention being to provide electronic means whereby a second magnetic field and transformer action are produced to influence and control the traveled distance and the directive path of the moving electrons released within an electron tube.

Present electronic tubes may be considered as electronic valves so constructed that their elements may be thought of as "floating," that is, as connected by the actual electronic stream and the capacity effect between their various elements. Because of this condition the various fundamental circuits employed in electronics are limited. It is an important object of the present invention to make feasible electronic circuit designs, not so limited, and to make possible many additional, more efficient, and different applications of electrical energy in this field.

It is an established fact that a magnetic field may be used to change the speed and direction of movement of electrons in vacua and thereby bring about various desirable effects not available without such control of the electrons. However, present means and method of so controlling electrons are costly and complicated, and unstable in action and result, to an extent rendering them impractical for many possible uses. An important object of the present invention is to provide relatively inexpensive, compact, and efficient means for stable control of the character indicated, whereby the functioning of circuits wherein unstable operation causes difficulties is greatly improved, and whereby other circuits of great value in solving electrical engineering problems are made available.

Other important objects and advantages of the invention will be apparent from a reading of the following description and the appended drawings, wherein for the purposes of illustration only, preferred embodiments of the invention are shown.

In the drawings—

Figure 1 is a transverse vertical sectional view taken through an electronic transformer tube embodying the present invention.

Figure 2 is a horizontal sectional view taken along the line 2—2 of Figure 1 and looking downwardly in the direction of the arrows.

Figure 3 is an enlarged top plan view of the cylindrical split plate of the tube.

Figure 4 is a schematic diagram of the electrical relation of the elements of the tube.

Figure 5 is an enlarged perspective view of one of the sections of the plate.

Figure 6 is a similar view of another section. Figure 7 is an enlarged side elevational view of the helical grid coil and supports.

Figure 8 is a top plan view of Figure 7.

Figure 9 is a perspective view of one of the grid helix supports and plate section insulators.

Figure 10 is a perspective view of another of the helix supports and plate section insulators.

It is a well known fact that an electron projected into a magnetic field will reverse its motion when that magnetic field is at right angles to the direction of travel of the electron, and further that when a static charge field is present also the deflecting pull on the electron is the vector resultant of the charge field and the magnetic field.

The purpose and function of the herein disclosed device is to bring about a second magnetic field and transformer action to influence and control the traveled distance and the directive path of the moving electron, and further to provide more than one critical point of operation.

Referring in detail to the drawings, the said device consists of an evacuated glass vessel 2 containing a cylindrical heater and electron emitter 25 F₁F₂K, a split cylindrical plate P₁P₂, and a helical grid coil G₁G₂, all properly supported and completely insulated by pillars 6 of rectangular shape, said pillars being supported by metal rods 7 which are embedded in glass foundation 9. The elements G₁G₂ and P₁P₂ are co-axial with F₁F₂K so that G₁G₂ lies in the intervening space between P₁P₂ and F₁F₂K. The proper leads are brought out through the glass foundation 9, and one lead G₁ is brought out of the vessel top through seal 35 and cap 1.

The cylindrical heater and electron emitter F₁F₂K is of the ribbon filament packed type where the emitter or cathode K has its outside surface coated by metallic oxide compounds, such coating 40 preferably comprising oxides of barium and strontium which operate at temperatures of the order of 1150° K., substantially lower than those possible with thorium and tungsten. The thickness of the coating is approximately one molecule. K is of 45 nickel.

The helical grid coil G₁G₂ is suspended by the four pillars 6 and is threaded through holes 4 which completely insulate the helical turns one from the other. The coil is continuous so that 50 an E. M. F. applied to G₁G₂ will cause a current to flow through the helix thereby producing a magnetic field at right angles to the path of the emitted electrons of K. G₁G₂ has a low coefficient of expansion and is a good electrical conductor.

The split plate cylinder, of iron or alloy, is made in four sections held together by rivets 8' passing through holes 8 in the insulating pillars 6 except where the longitudinal slit occurs. At this point the insulation is complete so that an E. M. F. applied to P_1P_2 will cause a current to flow through P_1P_2 and a magnetic field will be produced at right angles to the path of the emitted electrons of K. The insulator rings 3, two in number, and borne by the two rod supports 7 maintain the rigidity of support. The rings 3 bear against the glass vessel 2.

Figure 4 illustrates a schematic electrical diagram where the transformer connections are shown. G_1G_2 may serve as the transformer primary while P_1P_2 may serve as the transformer secondary or vice versa. At the same time P_1P_2 surface acts as the static charge plate and the G_1G_2 surface acts as the static charge control grid, all in relationship with the electron emitter K. FF is the heater to heat K. Because of the arrangement of P_1P_2 and G_1G_2 an alternating E. M. F. applied to G_1G_2 will induce a current in P_1P_2 90° out of phase. The transformer ratio is dependent upon the number of turns of the G_1G_2 helix since the P_1P_2 is a fixed split loop. Also, as a result of this arrangement the magnetic fields of G_1G_2 and P_1P_2 are parallel and almost colinear. It is possible, therefore, to have

the P_1P_2 field and the G_1G_2 field exist separately or to add or subtract vectorially.

The electron is born in the G_1G_2 magnetic field and is directed accordingly then when the G_1G_2 field diminishes the P_1P_2 magnetic field builds up and directs the electron accordingly. The phase difference is 90° for fundamental operation, however the effective control can be altered by applying another E. M. F. at P_1P_2 since it is the differential of the two magnetic fields and the static charge field that brings about the variable and final control. Thus, there is a wide range of control rather than just one critical point where operation begins. Because of this novel and useful feature remote control apparatus of which the electronic transformer is a part, is greatly simplified and accuracy of control is definite.

What is claimed is:

An electronic transformer comprising an evacuated envelope, a helical grid supported therein, a cathode and heater filament element coaxially mounted within said helical grid, insulating pillars extending radially from said grid, an open sided cylindrical plate within said envelope, surrounding and circumferentially spaced from said helical grid, said cylindrical plate being provided with flanges securing said pillars.

CHARLES F. WILCOX.
